John Stephenson, of New York, N.Y.

DES. 1962

Letters Patent No 1962-Dated June 14th 1864

Design for an Axle Box for R.R. Cars.

The schedule referred to in these Letters Patent and making part of the same.

To all whom it may concern,

Be it known that I, John Stephenson, of the City, County and State of New York, have invented or produced a new and original design for an Axle Box for Railroad Cars and I do hereby declare that the following is a full, clear and exact description of the same, reference being had to the accompanying drawing making a part of this specification, said drawing being a perspective view of my design.

The axle box is of quadrilateral form its top and bottom being at right angles with its sides the same as an ordinary axle box.

The front of the axle box has a curved cover or door A, projecting outward and extending downward as shown clearly in the drawing, the lower part of the door extending a trifle inward with a gradual curve.

The lower part B of the front of the axle box below the door A, also extends inward and is provided with a projecting bolt socket B, having a central and upright position on B.

At the rear of the axle box there are two vertical projections C, one at each side.

The front of the axle box and the vertical projections C, at its rear constitute all the novel parts of the design.

Having thus described my invention, I claim as new and desire to secure by Letters Patent:

The curved cover or door A, and inclined lower part B, of the front of the axle box with the vertical projections C, at the rear of the same, forming a new and original design therefor.
